UNITED STATES PATENT OFFICE.

OSCAR C. KAVLE, OF SYRACUSE, NEW YORK, ASSIGNOR TO E. FREDERICS, INC., OF NEW YORK, N. Y., A CORPORATION OF NEW YORK.

COMBINATION CLIP AND SHIELD FOR HAIR-WAVING DEVICES.

Application filed May 1, 1924. Serial No. 710,319.

To all whom it may concern:

Be it known that I, OSCAR C. KAVLE, a citizen of the United States of America, of Syracuse, in the county of Onondaga, in the State of New York, have invented new and useful Improvements in Combination Clips and Shields for Hair-Waving Devices, of which the following, taken in connection with the accompanying drawings, is a full, clear, and exact description.

This invention relates to a combined self-locking clip and shield for use in connection with hair waving and curling implements in which a relatively small number of strands of hair are tightly wound upon a bobbin from points close to the scalp and inclosed in a tubular capsule or pad containing borax or other suitable material thus forming a core which is placed within a paper tube of sufficient length to extend beyond the free ends of the coil of hair and corresponding end of the bobbin and close to the scalp.

The outer end of the tube is then closed by cotton or equivalent material and the inner end adjacent the scalp is compressed tightly around the adjacent portions of the hair after which heat is applied to the assembled parts sufficient to convert the moisture in the borax pad into steam vapor and to liberate the oil from the hair after which the tubes and bobbins are removed and the hair dressed to impart to it the desired permanent wave.

It is customary to treat several strands of hair in this manner simultaneously or in quick succession in order to secure uniform results in all of the strands and to prevent the hair from becoming excessively dry and brittle after the removing of the tubes and bobbins.

It is highly important therefore, to provide simple and efficient means for quickly compressing the end of the tube adjacent the scalp and holding it in its compressed position to prevent the passage of the steam to the scalp and consequently irritation thereof by blistering and while I am aware that various devices have heretofore been provided for partially effecting a tight compression of the end of the tube adjacent the scalp, they have been more or less inefficient in that they loose their compression force by loosening and opening under the pressure of the expanded vapor on the inside of the tube.

The main object therefore, of my present invention is to combine a self-locking clip and shield which will remain in its adjusted closed position irrespective of the pressure upon the interior of the tube tending to open the clip.

Another object is to provide the free ends of the jaws of the clip with finger pieces by which they may be opened and closed at will.

Other objects and uses relating to specific parts of the clip will be brought out in the following description.

In the drawings:

Figure 1 is a longitudinal sectional view of a strand of hair coiled upon a bobbin and its inclosing pad and heating tube together with my improved clip for compressing the inner end of the tube around the strand of hair adjacent the scalp.

Figure 2 is a plan of the detached clip in its closed position.

Figure 3 is a plan of the same clip showing the jaws in their open positions.

Figure 4 is a sectional view taken on line 4—4, Figure 2.

In order that the invention may be clearly understood, I have shown a strand —A— of hair coiled around a suitable bobbin —B— and encased in a borax-containing pad —C— which in turn is inclosed in a paper tube —D— extending from a point near the scalp to some distance beyond the free ends of the coil of hair and bobbin and having its outer end closed by a porous plug —E— of cotton or equivalent material, the end of the tube adjacent the scalp being compressed by my improved clip —1— after which the assembled parts within the tube —D— are heated to convert the moisture of the pad into steam which in turn acts upon the coil of hair to liberate the oil therefrom and thereby to prepare the strand of hair for future treatment to produce the desired permanent wave in a manner well known in this art and not necessary to herein further describe for the reason that the method of treating the hair forms no part of my present invention.

The clip —1— comprises a split jaw —2— and a cooperative jaw —3—, said jaws being made of thin sheet metal and hinged to each other at one end by a pivotal pin or rivet —4— which permanently holds them in operative relation.

The central portions of these jaws are concavo-convex in plan and arranged with their concave sides facing each other and preferably smooth for grasping and compressing the inner end of the tube —D— close to the scalp.

The jaw —2— is split or divided in a plane at right angles to the axis of the pivot —4— to form a slot —5— in which the jaw —3— is pivoted and adapted to move so that when the jaws are closed the opposed walls of the slot —5— or rather the parts of the jaws —2— at opposite sides of said slot engage opposite faces of the jaw —3— thereby holding the free ends of said jaws against accidental lateral springing movement and consequently release one from the other by the expansive pressure exerted thereon by the steam generated within the tube.

As illustrated, the jaw —2— is composed of two parts or sections, viz., a main part —6— and a supplemental part —7—, the main part —6— being of substantially the same form as the jaw —3— so that both parts may be stamped by the same die.

The part —7— however, is somewhat narrower but follows the general contour of the part —6— and is riveted thereto by the pivotal pin —4— and by an extra rivet —8— having a spacing collar —9— of substantially the same thickness as the slot —5— to assist the interposed portion of the jaw —3— in holding the parts —6— and —7— in spaced relation to form the slot —5—.

The rivet —8— is located relatively nearer to the pivotal pin —4— than to the free end of the jaw —2— leaving the remaining portions of the parts —6— and —7— free to spring apart for releasing the jaw —3— from between them in a manner presently described.

The jaw —3— and jaw section —6— are provided with inwardly projecting tongues —9— and —9'— some distance from the pivot —4—, the tongue —9— being provided with a series of apertures —10— arranged in sequence concentric with the axis of the pivot —4— while the tongue —9'— is provided with an upwardly pressed nib or detent —11—, the same distance from the axis of the pivot —4— as the apertures —10— for successively engaging said apertures as the jaws are closed one upon the other and locking the jaws in their closed positions.

The walls of the apertures —10— nearest the point of the tongue —9— are substantially flat and radial to the pivot —4— while the edge of the detent —11— farthest from the pivot of the tongue —9— is also flat and radial to said pivot for engaging the flat sides of the openings —10— and thereby producing a more effective lock for holding the jaws in their closed positions, while at

the same time permitting the detent —11— to ride freely along the adjacent face of the overlying tongue —9— when closing the jaws.

Both of the jaws are provided with integral extensions —12— substantially radial to their pivot —4— to form handles projecting beyond the tongues —9— and —9'— for closing and opening the jaws.

The part 7 extends along the tongue —9'— and is tensioned to spring toward the part —6— to impinge the tongue —9— of the jaw —3— between the parts —6— and —7— when the jaws are closed and thereby to more effectively hold said jaws against relative lateral displacement when closed upon the inner end of the tube —D— for compressing the same.

The free end of the jaw section —7— overlies the detent —11— so that when the apertured tongue —9— is inserted between the tongue —9'— and adjacent portion of the jaw section —7—, the tongue —9— will be pressed firmly between the jaw sections —6— and —7— to hold the detent —11— in interlocking engagement with the registering aperture —10—.

The free end of tongue —9'— and adjacent end of the jaw section —7— are curved outwardly in opposite directions at —13— to permit the tongue —9— to readily enter between the sections —6— and —7— when closing the jaws.

What I claim is:

1. The combination with a heating tube 100 of a hair waving device, of a clip and scalp protector adapted to be clamped to and seal the end of the tube close to the scalp, said clip comprising a pair of jaws pivoted to each other, one of said jaws being provided with a lengthwise slot for receiving a portion of the other jaw, and cooperative means on the jaws for locking them in their closed positions.

2. A combined clip and scalp shield as in 110 claim 1, in which the cooperative means for holding the jaws in their closed positions includes apertures in one of the jaws arranged in sequence concentric with the pivot, and a detent on the other jaw projecting 115 into the slot for engaging in any one of the apertures of the first named jaw.

3. A combined clip and scalp shield for hair waving appliances comprising opposed jaws, one of said jaws having opposed plates 120 forming an intervening slot, the other jaw being pivoted to and between said plates of the first named jaw, and means for locking the jaws in their closed positions, said jaws being provided with extensions forming handles by which the jaws may be opened and closed.

4. A combined clip and scalp for hair waving appliances comprising opposed jaws pivoted to each other and having their outer 130

ends provided with handles by which they may be opened and closed, one of said jaws having a yielding section and a main section, the other jaw having a portion thereof movable between the main section and yielding section, and means for locking the jaws in their closed positions.

5. A combined clip and scalp shield for hair waving appliances comprising opposed jaws pivoted to each other, one of said jaws having a slot for receiving a portion of the

other jaw, the portion of the first named jaw at one side of the slot being yielding, said jaws having cooperative means for locking them in their closed positions. 15

In witness whereof I have hereunto set my hand this 22nd day of April, 1924.

OSCAR C. KAVLE.
